ATTORNEY

UNITED STATES PATENT OFFICE.

ELMER M. AXNESS, OF MONTEVIDEO, MINNESOTA.

TOILET KIT.

Application filed May 2, 1924. Serial No. 710,672.

To all whom it may concern:

Be it known that I, ELMER M. AXNESS, a citizen of the United States, residing at Montevideo, in the county of Chippewa and State of Minnesota, have invented new and useful Improvements in Toilet Kits, of which the following is a specification.

This invention relates to toilet kits or accessories and has for an object the provision of a case adapted to contain a dentifrice and a tooth brush arranged so as to be conveniently carried in the pocket and to provide a dust and germ proof container capable of admitting air to the brush.

With the above and other objects in view, the invention further includes the following novel features and details of construction, to be hereinafter more fully described, illustrated in the accompanying drawings and pointed out in the appended claim.

In the drawings:-

Figure 1 is an elevation of the invention.

Figure 2 is a longitudinal sectional view of the same.

Figure 3 is a transverse section on the line 3—3 of Figure 1 with the brush and dentifrice removed.

Figure 4 is an enlarged fragmentary section taken longitudinally of the brush handle.

Referring to the drawings in detail wherein like characters of reference denote corresponding parts, the device as illustrated comprises a case 10 which is open at one side and provided with a telescopic cover 11, the latter extending over the open end and the sides of the case.

The case is provided with inwardly disposed depressions 12 which extend inwardly

from opposite side walls of the case, the 40 walls of the depressions being spaced apart so as to provide together with the cover 11, air passages 13 which open at their top into the case to provide ventilation. The depressions 12 also divide the case into compartments 14 and 15, the former being adapted to contain a tube 16 of dentifrice while the latter is adapted to contain a tooth brush 17. The handle of the brush is provided with a telescopic extension 18 which 50 is connected to the handle proper through the medium of a pin 19 which extends into a slot 20 of the extension.

By constructing the case in the manner shown it is adapted for conveniently carrying a tooth brush and a tube of tooth paste, while the ventilating passages 13 provide proper ventilation for the brush without exposing the latter to dust or germs.

If desired, the cover 11 may be provided 60 with a mirror 21 upon one side thereof.

The invention is susceptible of various changes in its form, proportions and minor details of construction and the right is herein reserved to make such changes as properly fall within the scope of the appended claim.

Having described the invention what is claimed is:-

A toilet kit comprising a case open at one end, a telescopic cover for the case, oppositely located depressions extending inwardly from opposite sides of the case and defining combined ribs to divide the case into a dentifrice compartment and a tooth brush compartment and to provide air passages between the case and cover.

In testimony whereof I affix my signature.

ELMER M. AXNESS.
